United States Patent Office

Des. 183,865
Patented Nov. 4, 1958

183,865

TABLE KNIFE

Magnus L. Stephensen, Copenhagen, Denmark
Application February 4, 1957, Serial No. 44,742

Term of patent 14 years
(Cl. D22—3)

Figure 1 is a side elevational view of a table knife illustrating my new design;

Figure 2 is a bottom edge view thereof;

Figure 3 is a top edge view; and

Figure 4 is a sectional view thereof taken on the line 4—4 of Figure 1.

I claim:

The ornamental design for a table knife, as shown.
